UNITED STATES PATENT OFFICE.

HARRY F. KEIFFER, OF PERRYSBURG, OHIO.

ТИЛТИНГ ВАШЕР.

Application filed February 18, 1926. Serial No. 89,067.

This invention relates to washing machines, but particularly to washing machines of the "tilting" or "wave" type wherein the agitation of the soapy water and clothes is produced by causing the water to rise above and dash upon the clothes by a tilting action of the container.

Objects of this invention are to provide a simple and improved cellular arrangement for washing machines which is capable, more efficiently, of alternately creating a suction and outward forcing of the water and air in the inside of the machine so as thoroughly to cleanse the fabric within a minimum period of time; to provide improved means for attaching the cellular member in operative position in the machine; and, in general to provide a tilting washer having the new and improved features of construction and arrangement hereinafter more particularly described.

In some respects this invention relates to my United States Patent 1,574,488, issued February 28, 1926. An outstanding characteristic of this invention resides in inclining portions of the cellular members in opposite directions and preferably these portions are inclined in the direction of the water passage when tilted in one direction or the other. The advantage of this arrangement is apparent in that the water flow is facilitated from one side of the washer to the other and by effecting a more facile flow the washing operation is made more efficient because the machine may be tilted from side to side more rapidly and consequently the rate of blowing and sucking operations are increased.

Another cardinal feature of the invention consists in the provision of means for detachably connecting the cellular members within the washer. Preferably a plurality of members are employed and each may be conveniently removed for purposes of cleansing or for other reasons. Furthermore, it is contemplated to so form the bottom wall of the container in such a manner that the cells are of uniform length so that the several cells will be equally effective.

The invention is shown by way of illustration in the accompanying drawings, in which:

Fig. 1 is a transverse sectional view of a washing machine embodying my invention; Fig. 2 is a section on the line 2-2 of Fig. 1;

and Figure 3 is an enlarged section on the line 3-3 of Figure 1.

The illustrated embodiment of the invention comprises a container 1 having an opening 2 extending across the top of the container and this opening is closed by a cap 3. The fabric to be washed may be placed in and removed from the container through the opening 2. The bottom wall 4 of the container is preferably rounded in the manner shown for a purpose herein-after described.

The container is supported on a standard 5 which is connected to arms 6 on the container by a stub shaft 7 at a point below the middle part of the container 1. The stub shaft 7 may be oscillated by any suitable or preferred means.

Extending across the container 1 in the region of the bottom wall 4 and spaced a slight distance therefrom is a wedge shaped spacer member 8 of sheet metal such as galvanized iron, and the opposite ends of the spacer 8 may be connected to the side walls 80 of the container in any suitable manner.

Arranged within the container 1 and engaging the opposite sides of the spacer 8 are cellular members 9 and 10 which incline in opposite directions from the spacer. It will be seen that each cellular member 9 is made up of vertically disposed inclined side walls 11 and, in this instance the top wall 12 is tapered to a point so that the top of each cellular member forms a corrugated 90 surface. The inner or bottom ends of the cellular member are open, and the upper ends are formed with perforations 13. The open inner or bottom ends are spaced a slight distance from the bottom wall of the container thereby providing passage or channel 14.

By inclining the cellular members in opposite directions and curving the bottom wall 4 of the container after the manner indicated on the drawings, it will be noted that the cells are of substantially the same length throughout, so that effectiveness of each individual cell is practically the same as every other cell. This also provides a less restricted flow of water through the several cells.

Extending across the opposite ends of the container 1 and arranged in vertically disposed relation are plates 15 which are spaced from the side walls and may be connected by any suitable means to the inside of the

container. These plates are provided with perforations 16 and the lower ends engage the adjacent cell to assist in holding the cellular members in position. Each cellular member may be removed from the container by slightly compressing the structure so as to clear the lower edge of the adjacent plate 16 and then by lifting upwardly the structure may be separated from its holding 10 means.

When the container is tilted about the axis of the stub shaft 7, the water moves along the top of the cellular members, is thrown toward the opposite side and dashes 15 on to the top of the fabric material as will readily be understood. This movement of the container carries the bulk of the water in the channel 14 and cells from one end of the container to the other end.

20 This action draws the mist or vapor formed by the dashing water within the container 1 through the fabric and particularly the material in contact with the cellular member which is in upwardly tilted 25 position. On the return of the container the mist and air which were sucked or drawn into the cellular member are forced out through the material thereabove.

On further movement of the container the 30 opposite cellular member is emptied of water, a part of which flows through the channel 14, and a suction action is produced at that end of the container. It will thus be seen that oscillation of the container back and forth throws practically all the water from the channel 14 and this creates an alternate drawing in and forcing out of mist, water and air which thoroughly and efficiently cleans the material within the 35 container.

40 While the form of mechanism here shown and described is admirably adapted to fulfill the objects primarily stated, it is to be understood that it is not intended to confine the invention to the one form of embodiment herein disclosed, for it is susceptible of embodiment in various forms all coming within the scope of the claims which 45 follow.

50 What I claim as new and desire to secure by Letters Patent is:

1. In a tilting fabric washing machine, a container and a cellular structure consisting of a plurality of cells having open lower 55 ends spaced from the bottom of said container thereby providing a channel and having openings in the upper ends of the cells, the cells on one side of the container being inclined in one direction from the vertical 60 plane of the container and the cells on the opposite side being inclined in the opposite direction.

2. In a tilting fabric washing machine, a

container, removable cellular members each having a plurality of cells formed with open 65 lower ends spaced from the bottom of said container thereby providing a channel and having openings in the upper ends of the cells, the cells being inclined in opposite directions from the center of the container, 70 and a spacer member for separating said cellular members from each other.

3. In a tilting fabric washing machine, a container, a plurality of cellular members each having a plurality of cells formed with 75 open lower ends spaced from the bottom of said container thereby providing a channel and having openings in the upper ends of the cells, the cells being inclined in different directions from the center of the container, 80 and a spacer member disposed between said differently inclined cellular members.

4. In a tilting fabric washing machine, a container, a plurality of removable cellular members each having a plurality of cells 85 formed with open lower ends spaced from the bottom of said container thereby providing a channel and having openings in the upper ends of the cells, the cells being inclined in opposite directions from the center 90 of the container, a spacer member between said oppositely inclined cellular members and a perforated plate extending across said container at opposite sides thereof and engaging the upper portions of adjacent cellular 95 members for holding the latter in position.

5. In a tilting fabric washing machine, a container, a plurality of removable cellular members having a corrugated top and consisting of a plurality of cells having open 100 lower ends spaced from the bottom of the container thereby providing a channel and having openings in the upper ends of the cells, a wedge shaped spacer in the central portion of the container having oppositely 105 inclined sides, the cells being inclined in opposite directions from opposite sides of said spacer, and a perforated plate extending across each side of said container and engaging upper portions of the adjacent cellular 110 members for holding the latter in position.

6. In a tilting fabric washing machine, a container, cellular means having a plurality of cells formed with open lower ends spaced from the bottom of said container to provide a common channel and also formed with openings in the upper ends, said cellular means being spaced at opposite ends from the adjacent sides of the container to enable the liquid to flow freely to and from said 115 channel, and means for holding said cellular means in position.

In testimony whereof I have hereunto signed my name to this specification.

HARRY F. KEIFFER.
